UNITED STATES PATENT OFFICE.

ULYSSIS A. SHIREY, OF KANSAS CITY, MISSOURI.

CORN-HARVESTER.

1,099,210.

Specification of Letters Patent.

Patented June 9, 1914.

Application filed March 28, 1912. Serial No. 686,830.

To all whom it may concern:

Be it known that I, ULYSSIS A. SHIREY, a citizen of the United States, residing at Kansas City, in the county of Jackson, State 5 of Missouri, have invented certain new and useful Improvements in Corn-Harvesters; and I do hereby declare the following to be a full, clear, and exact description of the invention, such as will enable others skilled in 10 the art to which it appertains to make and use the same.

This invention relates to new and useful improvements in corn harvesters.

An object of this invention is the 15 vision of a corn husker which will cut the standing corn and convey the same into the path of the operating mechanism.

A still further object of this invention is to improve and simplify devices of this 20 character, rendering them comparatively simple and inexpensive to manufacture, reliable and efficient in use and readily operated.

With the above and other objects in view, 25 this invention resides in the novel features of construction, formations, combinations and arrangements of parts to be hereinafter more fully described and illustrated in the accompanying drawings, in which:

30 Figure 1 is a side elevation of my improved husker. Fig. 2 is a top plan view thereof. Fig. 3 is a horizontal sectional view taken on the line 3—3 of Fig. 1. Fig. 4 is a horizontal sectional view taken on the 35 line 4—4 of Fig. 1. Fig. 5 is a rear elevation with portions removed. Fig. 6 is a cross sectional view taken on the line 6—6 of Fig. 1 with the rear wheeled axle in elevation. Fig. 7 is a cross sectional view taken 40 on the line 7—7 of Fig. 1, and Fig. 8 is a cross sectional view taken on the line 8—8 of Fig. 1.

45 Referring to the accompanying drawings by similar characters of reference throughout the several views, the numeral 10 designates generally my improved husker which comprises a frame 11 consisting of upper and lower longitudinal bars 12 and 13 connected at their ends by upper and lower 50 cross bars 14 and 15 and at intervals throughout their length by vertical bars 16. A suitable platform or engine bed 17 is supported by the intermediate bars 16 adjacent their upper terminals and supports an engine 18. 55 The forward terminals of the bars 13 are

prolonged as shown at 19 and are connected at their free extremities by a transverse bar 20.

A pair of spaced shoes 21 are secured to the bar 20 extending forwardly therefrom 60 and have slidably therein a cutter bar 22 which has secured to its upper side a plurality of blades 23 which coöperate with the guard fingers 24 and serve to cut the stalks of corn engaged thereby. The cutter bar 22 65 has pivotally secured to one end a link 25 connected to the wrist pin 26 which extends eccentrically from the disk 27 keyed to the forward terminal of a countershaft 28 journaled in suitable bearings 29 attached to one 70 of the bars 13 and the prolongation thereof of 19.

The frame 11 has journaled at its rear end an axle 30 carrying keyed at its opposite terminals rear traction wheels 31. This axle 75 30 has securely keyed thereon a beveled pinion 32 which meshes with a similar pinion 33 keyed to the shaft 34 which is connected to the shaft 28 by means of a knuckle joint 35 and serves to cause the operation of the 80 cutter bar 22 upon the rotation of the axle 30. The front axles 36 are secured beneath the forward end of the frame 11 and carry the front supporting wheels 37. A pair of vertical bars 38 are secured to the ends of 85 the axles 36 and extend for vertical movement through the guides 39 secured to the bars 12 and 13. The upper ends of the rods 38 are connected by a bar 40 which is provided intermediate its ends with a pair of 90 spaced ears 41 between which is pivoted a lifting lever 42 fulcrumed at one end as at 43 to a vertically extending bracket 44 secured to the front bar 14. A pawl 45 is mounted upon the free end of the lever 42 95 and is operated so as to be thrown into and out of engagement with a segmental rack bar 46 by a hand lever 47. The bracket 44 and the rack bar 46 are connected to the frame 11 by suitable braces 48. Obviously 100 when the lever 42 is raised or lowered by the person who may sit in the operator's seat 48', the forward end of the frame 11 will be raised or lowered with respect to the wheels 37. The rods 38 have extending forwardly 105 therefrom crank arms 49 which are connected by crossed links 50 to a pair of crank arms 51 which extend laterally from the steering standard 52 which is equipped with a hand wheel 53 upon the rotation of which 110

the wheels 37 will be moved to guide the machine. A pair of shafts 54 and 55 are journaled within the frame 11 adjacent the bottom thereof and are connected by a suitable conveyer 56 which carries the stalks of corn deposited thereon to a pair of superposed rollers 57 and 58 keyed upon the shafts 59 and 60 journaled upon the rear bars 16. The shafts 59 and 60 are rotated in opposite directions by a chain drive 61 from the shaft 55 and a chain drive 141 from a shaft 66.

As the stalks of corn are moved rearwardly of the frame 11 upon the upper lap of the conveyer 56, the same will be positively driven between the rollers 57 and 58 by a conveyer 62 supported by a pair of rollers 63 and 64 keyed to the shafts 65 and 66 journaled upon the intermediate uprights 16. A baffle plate 67 which is preferably curved in cross section causes the stalks to be moved beneath the conveyer 62 endwise with respect to the longitudinal axis of the said conveyer. As the corn stalks are forced beneath the roller 57 the ears will be stripped therefrom and be dropped into the lower end of the transverse conveyer casing 68 in which is located a conveyer 69 supported by a pair of rollers 70 and 71. The said casing 68 extends transversely of the frame 11 and is then extended upwardly as at 73 terminating in a discharge chute 74 for a purpose to be later disclosed. In order to provide for the turning of the conveyer in the elbow 35 of the casing the flights 75 terminate at the ends short of the side edges of the conveyer belt 76, the marginal edges of which are engaged by rollers 77 which hold the conveyer from contact with the conveyer casing.

The shaft 78 which supports the driven roller 70 of the conveyer is equipped with a sprocket wheel 79 connected by a chain 80 to a sprocket 81 keyed to the adjacent terminal of the countershaft 82, the said shaft 45 being journaled in suitable bearings 83 supported by one of the bars 13 and provided at its opposite end with a pinion 84 engaging the above mentioned gear 32 secured to one of the drive wheels 31 thus providing a 50 means for operating the conveyer. A pair of guide plates 86 are secured to the front end of the frame 11 in any suitable manner and are converged inwardly at their intermediate points as indicated by the numeral 55 87. A pair of shafts 88 and 89 are journaled upon the ends of the plates 86 and have keyed thereon sprocket wheels 90 over which pass conveyer chains 91 formed with teeth 92 and when the inner laps of the 60 chains which ride upon the inner faces of the plates are propelled rearwardly, and during advance of the machine the said teeth will engage the corn stalks which have been severed adjacent the ground by the cutting blades 23 drawing the same inwardly for

engagement with the baffle plate 67 causing them to be disposed lengthwise upon the conveyer 56.

The upper extremities of the shafts 89 have keyed thereon beveled pinions 93 which mesh with similar pinions 94 keyed to a transversely extending shaft 95 journaled in suitable bearings 96 attached to the upper edge of one of the bars 14. The shaft 95 has securely keyed thereon a beveled pinion 97 which meshes with a beveled pinion 98 carried by the upper terminal of a vertical counter shaft 99 supported in bearings 100 secured at convenient points upon the frame 11. The lower terminal of the shaft 99 is 80 provided with a beveled pinion 101 which meshes with a similar pinion 102 carried by the shaft 28 thus providing a means for operating the chains 91 upon the rotation of the said shaft 28.

A husking frame 119 is secured to the uprights 16 below the mouth of the chute 74 and comprises a pair of side plates 120 connected at their terminals by end plates 121 which latter have journaled therein a plurality of husking rollers 122 formed with radially projecting fingers 123. The shafts are rotatably connected by a chain of gear wheels 124 which are driven by a gear wheel 125 keyed to a shaft 126 to the outer end of which is fixed a sprocket wheel 127 connected by a sprocket chain 128 to a sprocket wheel 129 keyed to the drive shaft 130 to the engine 18. A second sprocket wheel 131 is also keyed to the drive shaft 130 and is 100 connected by a sprocket chain 132 to a sprocket wheel 133 carried by a transverse shaft 134 journaled upon the intermediate uprights 16. This shaft 134 has keyed thereon adjacent the sprocket wheel 133, and at its terminal a pair of sprocket wheels 135 and 136, over the former of which passes a chain to a sprocket wheel 137 carried by the shaft 65 by which provision is made to impart motion to the conveyer 62, while the 110 chain 138 passes over the sprocket wheel 136 and over a wheel 139 carried by the rear axle 30 and serves to provide for the driving of the traction wheel 31 and various operating elements connected to the said shaft 110. The shaft 66 is provided with a sprocket wheel 140 over which passes a chain 141 for engagement with a sprocket wheel 142 serving to cause the rotation of the roller 57. The shaft 126 is provided 120 with a pulley 142' for engagement with a belt 143, which through the medium of a pulley 144 serves to impart a rotary movement to the shaft 145 and drive the conveyer belt 146 rearwardly so that the shucks 125 after being removed from the ears of corn by rollers 122 will be conveyed to the rear extremity of the machine and deposited together with the stalks which pass through the rollers 57 and 58 upon a dumping frame 130

147 operated by a lever 148 fulcrumed upon the frame 11 as at 149 and which is connected to the arm 150 of the dumping frame by a link 151. The lever 148 is locked 5 against movement by the engagement of its pawl 152 with a segment 153 supported also by the frame 11. The rear end of the conveyer belt 146 passes over a roller 154 carried by a shaft 155 which in turn is connected to 10 the shaft 55 by a sprocket chain 156 which passes over sprocket wheels 157 and 158 carried by the shafts 155 and 55 respectively.

As clearly illustrated in Fig. 6 of the drawings, the rollers 122 slant toward one 15 side of the frame 11 at which point is located the mouth 158' of a vertical chute 159 which is secured to the said frame 11. This chute comprises a casing which is substantially rectangular in cross section and which 20 has extending from its lower end an inclined casing 160 provided with a depending spout 161 beneath which is preferably located a wagon or other suitable container (not shown in the drawings). A pair of shafts 25 162 and 163 are journaled in the opposite ends of the extension 160 to support rollers 164 and 165 over which passes a conveyer belt 166 by means of which the husked ears will be deposited into the said container 30 (not shown in the drawings). The shaft 162 has keyed thereon a sprocket wheel 167 which engages a sprocket chain 168 connected at its opposite end to a sprocket wheel 169 carried by the shaft 34.

35 The operation of the machine is as follows: The forward end of the frame is first adjusted with respect to the front supporting wheels 37 to its proper height in order that the blades 23 will sever the stalks at 40 a proper distance from the ground. Power is then applied to the rear axle 30 and the machine is propelled over the ground by the traction wheels 31, being guided by the steering mast 52. As the guard fingers 24 engage the corn stalks the latter will be thrown between the blades 23 and upon the oscillation of the cutter bar 22 will be severed and deposited lengthwise upon the upper lap of the conveyer 56 by toothed chains 45 50 91 and baffle plate 67. As the upper lap of

the conveyer 56 moves rearwardly the stalks will be forced lengthwise between the rollers 57 and 58 by the conveyer 62. The ears of corn will be obviously stripped therefrom and permitted to drop into the casing 72 55 from whence they will be conveyed upwardly through the extension 73 and deposited through the chute 74 upon the husking rollers 122. The stripped stalks will pass through the rollers 57 and 58 and be deposited upon the dumping frame 147. Upon the rotation of the husking rollers 122 the radial fingers 123 will strip the husks from the ears causing the same to be dropped through the rollers upon the conveyer 146 60 65 from whence they will be deposited upon the dumping frame 147. The husked ears will then pass downwardly through the chute 159 for the engagement with the conveyer 166 which will transfer them to the 70 container (not shown) through the spout 161.

From the foregoing disclosures taken in connection with the accompanying drawings, it will be manifest that a machine for cutting corn and removing the husks therefrom is provided which will fulfil all of the necessary requirements of such a device. 75

Having thus fully described this invention what I claim as new and desire to protect by Letters Patent, is:— 80

In a corn husker, a main frame, a cutter bar, a horizontal endless carrier in rear of said cutter bar having the upper lap moving rearwardly in said frame, a pair of vertically disposed endless carriers above said cutter bar and horizontal carrier and serving to carry stalks rearwardly in upright position upon said horizontal carrier, and an inclined baffle plate having an arched top 85 90 adapted to knock down the upright stalks into lengthwise position during passage of the stalks therethrough upon said horizontal carrier.

In testimony whereof, I affix my signature, 95 in presence of two witnesses.

ULYSSIS A. SHIREY.

Witnesses:

E. Y. SCHMITT,
GEO. H. DAILEY.
